UNITED STATES PATENT OFFICE

2,598,723

STEAM BOILER

William Sampson, Aldwych, London, England,
assignor, by mesne assignments, to Foster
Wheeler Corporation, New York, N. Y., a corporation of New York

Application June 2, 1944, Serial No. 538,363
In Great Britain July 6, 1943

12 Claims. (Cl. 122—240)

1

This invention has reference to steam boilers of the kind in which separately fired furnaces are arranged side by side and the gases from the one flow laterally into the other on their way to the uptake. When the furnaces of such boilers are fired with liquid, gaseous or pulverised fuel, fed to burners arranged at the one end of the furnaces, the gases of combustion flowing from the one furnace through the other are apt to interfere with combustion of the fuel issuing from the burners in the latter furnace unless directed away from the said burners. In some cases partitioning baffles or walls have been provided to direct the gases from the one furnace through the upper part of the other furnace above its burners or through the portion of the furnace remote from the burners so that the gases from the one furnace are confined to passage through only a comparatively small portion of the other furnace.

According to this invention in order to obtain distribution of the gases from one furnace over a greater portion of the other furnace and at the same time to protect the burners of the latter furnace from interference by said gases, a baffle is provided between the furnaces which is of sufficient depth at the burner end of the furnaces to prevent the gases from the one furnace flowing over the burners in the other with decreases in depth towards the other end of the furnaces thus enabling the gases from the one furnace to enter the other towards the end remote from the burners at a lower level and to become distributed through a gradually increasing depth of the said furnace.

In the accompanying drawing, Fig. 1 is a cross sectional elevation of a water tube boiler fitted with one form of baffle according to the invention, the view being taken looking from the rear of the boiler towards the front thereof. Fig. 2 is a side elevation of the baffle and one of the boiler drums. Figs. 3 and 4 are views at right angles to one another of part of a similar boiler showing a modified way of constituting the baffle, Fig. 5 being a horizontal section on the line 5—5, Fig. 3. Fig. 6 is a view similar to Fig. 1 but of another embodiment of the invention, which view is taken on the line 6—6 of Fig. 7, and Fig. 7 is a side elevation of the baffle shown in Fig. 6.

Like characters of reference refer to the same or similar parts throughout the several views.

As shown in Fig. 1, 1 represents the burner fired furnace from which gases of combustion flow laterally into the adjacent side furnace 2 on their way to the uptake 3. To prevent the gases of combustion from the furnace 1 passing over the burners 4 of the furnace 2, the baffle 5 is pro-

vided constituted by a firebrick wall which decreases in height from the end 6 adjacent to the front of the furnaces towards the other end.

In the modification shown in Figs. 3, 4 and 5, the water tubes of two rows 7, 8 are bent to make contact with each other for varying lengths in order to secure a baffle effect equivalent to that derived by the use of the baffle 5, Fig. 2.

The baffle also may be formed by filling the spaces between a flow of tubes to varying depth as illustrated in Fig. 6.

A tapering baffle as referred to may extend to the rear end 10 of the furnaces, as shown in Fig. 2, or may terminate short of the rear end 10 as shown in Figs. 3 and 5; also the decrease in its depth may commence at some distance from the front end 10 of the furnaces, as shown at 11 in Fig. 7, and it may continuously decrease in depth as in the embodiment of the invention illustrated in Figs. 1 to 5 or decrease in a number of steps 12 as shown in Fig. 7.

What I claim is:

1. A steam generator comprising a setting, a pair of spaced groups of generating tubes in the setting, a furnace chamber arranged between the steam generating tube groups, burner means for firing said furnace chamber, another furnace chamber in the setting disposed adjacent tubes of one of said tube groups and outside said first-mentioned furnace chamber, other burner means adjacent the first-mentioned burner for separately firing said other chamber, a single combustion gas outlet flue at the outer side of the other tube group and arranged to receive all of the gases flowing from both furnace chambers, said flue being so located that the heating gases from the other furnace chamber flow over both of the tube groups and through the first-mentioned furnace chamber before entering the flue, and baffle means between the furnaces, said baffle means being of such depth adjacent the burner means as to prevent gases from the other furnace from flowing over the first-mentioned burner means, the baffle decreasing in depth to such an extent in a direction away from the burners as to enable gases from said other furnace to enter the ignition and combustion zone of said first-mentioned furnace beyond the burner means therefor in the direction of flow of gases in said zone and mix with gases flowing from said burners to thereby become distributed throughout an area of the first-mentioned furnace chamber which gradually increases in a direction away from the burner means.
2. A steam generator comprising a setting, an upper steam and water drum, a pair of spaced lower water drums, a bank of inclined steam gen-

erating tubes connecting said upper drum to one of said lower drums, a group of steam generating tubes connecting the upper drum to the other of said lower water drums, a baffle arranged to divide the space between said tube bank and said tube group into a furnace chamber and another furnace chamber laterally adjoining said first-mentioned furnace chamber, burner means for firing the first-mentioned furnace chamber, other burner means adjacent the first-mentioned burner for independently firing the other furnace chamber, said burner means and said other burner means being disposed to direct a stream of gases of combustion in a horizontal direction, a single combustion gas outlet flue at the outer side of the tube bank and arranged to receive all of the gases flowing from both furnace chambers, said flue being so located that the heating gases from the other furnace chamber flow over the tube group, the tube bank and through the first-mentioned furnace chamber before entering the flue, said baffle being of such depth adjacent the burner means as to prevent gases from the other furnace from flowing over the first-mentioned burner means, the baffle decreasing in depth to such an extent in a direction away from the burners as to enable gases from said other furnace to enter the ignition and combustion zone of said first-mentioned furnace beyond the burner means therefor in the direction of flow of gases in said zone and mixed with gases flowing from said burners to thereby become distributed throughout an area of the first-mentioned furnace chamber which gradually increases in a direction away from the burner means.

3. A steam generator comprising a setting, an upper steam and water drum, a pair of spaced lower water drums, a bank of inclined steam generating tubes connecting said upper drum to one of said lower drums, a group of steam generating tubes connecting the upper drum to the other of said lower water drums, a substantially vertically extending baffle arranged to divide the space between said tube bank and said tube group into a furnace chamber and another furnace chamber laterally adjoining said first-mentioned furnace chamber, burner means for firing the first-mentioned furnace chamber, other burner means adjacent the first-mentioned burner for independently firing the other furnace chamber, said burner means and said other burner means being disposed to direct a stream of gases of combustion in a horizontal direction, and a single combustion gas outlet flue at the outer side of the tube bank and arranged to receive all of the gases flowing from both furnace chambers, said flue being so located that the heating gases from the other furnace chamber flow over the tube group, the tube bank and through the first-mentioned furnace chamber before entering the flue, said baffle being of such depth adjacent the burner means as to prevent gases from the other furnace from flowing over the first-mentioned burner means, the baffle decreasing in depth to such an extent in a direction away from the burners as to enable gases from said other furnace to flow laterally and enter the ignition and combustion zone of said first-mentioned furnace beyond the burner means therefor in the direction of flow of gases in said zone and mix with gases flowing from said burners to thereby become distributed throughout an area of the first-mentioned furnace chamber which gradually increases in depth in a direction away from the burner means.

4. A steam generator comprising a setting, a

pair of laterally spaced groups of generating tubes in the setting, a furnace chamber arranged between the steam generating tube groups, burner means at one end of said furnace chamber positioned to direct a stream of gases of combustion in a horizontal direction toward the opposite end thereof, another furnace chamber in the setting disposed adjacent tubes of one of said tube groups and outside said first-mentioned furnace chamber, other burner means for separately firing said other furnace chamber disposed at the same end of the setting as the first-mentioned burner means to direct a stream of gases of combustion in a horizontal direction toward the opposite end of the setting, a single combustion gas outlet flue at the outer side of the other tube group and arranged to receive all of said gases flowing from both furnace chambers, said flue being so located that the heating gases from said other furnace chamber flow over both of the tube groups and across the first-mentioned furnace chamber before entering the flue, and substantially vertically extending baffle means between the furnaces, said baffle means being of such depth adjacent the burner means as to prevent gases from the other furnace from flowing over the first-mentioned burner means, the baffle decreasing in depth towards the other end of the furnaces to such an extent as to enable gases from said other furnace to enter the ignition and combustion zone of said first-mentioned furnace beyond the burner means therefor in the direction of flow of gases in said zone and mix with gases flowing from said burners to thereby become distributed throughout an area of the first-mentioned furnace chamber which gradually increases in depth in a direction away from the burner means.

5. A steam generator comprising a setting, an upper steam and water drum, a pair of spaced lower water drums, a bank of inclined steam generating tubes connecting said upper drum to one of said lower drums, a group of steam generating tubes connecting the upper drum to the other of said lower water drums, a baffle arranged to divide the space between said tube bank and said tube group into a furnace chamber and another furnace chamber laterally adjoining said first-mentioned furnace chamber, burner means at one end of said furnace chamber positioned to direct a stream of gases of combustion in a horizontal direction toward the opposite end thereof, other burner means for separately firing said other furnace chamber disposed at the same end of the setting as the first-mentioned burner means to direct a stream of gases of combustion in a horizontal direction toward the opposite end of the setting, a single combustion gas outlet flue at the outer side of said tube bank and arranged to receive all of the gases flowing from both furnace chambers, said flue being so located that the heating gases from the other furnace chamber flow over the tube group, the tube bank and through the first-mentioned furnace chamber before entering the flue, and substantially vertically extending baffle means between the furnaces, of such depth adjacent the burner means as to prevent gases from the other furnace from flowing over the first-mentioned burner means, the baffle decreasing in depth towards the other end of the furnaces to such an extent as to enable gases from said other furnace to enter the ignition and combustion zone of said first-mentioned furnace beyond the burner means therefor in the direction of flow of gases

in said zone and mix with gases flowing from said burners to thereby become distributed throughout an area of the first-mentioned furnace chamber which gradually increases in depth in a direction away from the burner means.

6. A steam generator comprising a setting, a pair of laterally spaced groups of generating tubes in the setting, a furnace chamber arranged between the steam generating tube groups, burner means for firing said furnace chamber, another furnace chamber in the setting disposed adjacent tubes of one of said tube groups and outside said first-mentioned furnace chamber, other burner means adjacent the first-mentioned burner for separately firing said other chamber, said burner means and said other burner means being disposed to direct a stream of gases of combustion in a horizontal direction, a single combustion gas outlet flue at the outer side of the other tube group and arranged to receive all of the gases flowing from both furnace chambers, said flue being so located that the heating gases from the other furnace chamber flow over both of the tube groups and through the first-mentioned furnace chamber before entering the flue, and substantially vertically extending baffle means between the furnaces, said baffle means being of such depth adjacent the burner means as to prevent gases from the other furnace from flowing over the first-mentioned burner means, the baffle being tapered to such an extent from a point adjacent the burners in a direction away therefrom as to provide a flow area for gases from said other furnace chamber which area gradually increases in a direction away from the burner means and through which gases from the other furnace enter the ignition and combustion zone of said first-mentioned furnace beyond the burner means therefor and mix with gases flowing from said burners to thereby become distributed throughout an area of the first-mentioned furnace chamber which gradually increases in a direction away from the burner means.

7. A steam generator comprising a setting, an upper steam and water drum, a pair of spaced lower water drums, a bank of inclined steam generating tubes connecting said upper drum to one of said lower drums, a group of steam generating tubes connecting the upper drum to the other of said lower water drums, a substantially vertically extending baffle arranged to divide the space between said tube bank and said tube group into a furnace chamber and another furnace chamber laterally adjoining said first-mentioned furnace chamber, burner means at one end of said furnace chamber positioned to direct a stream of gases of combustion in a horizontal direction toward the opposite end thereof, other burner means for separately firing said other furnace chamber disposed at the same end of the setting as the first-mentioned burner means to direct a stream of gases of combustion in a horizontal direction toward the opposite end of the setting, a single combustion gas outlet flue at the outer side of said tube bank and arranged to receive all of the gases flowing from both furnace chambers, said flue being so located that the heating gases from the other furnace chamber flow over the tube group, the tube bank and through the first-mentioned furnace chamber before entering the flue, and baffle means between the furnaces, said baffle means at the end thereof adjacent said burners extending upwardly to a point beyond the burners to prevent gases from the other furnace from flowing over the first-mentioned

burner means, the upper edge of the baffle being tapered to such an extent from a point adjacent the burners in a direction away therefrom as to provide a flow area for gases from said other furnace chamber which area gradually increases in a direction away from the burner means and through which gases from the other furnace enter the ignition and combustion zone of said first-mentioned furnace beyond the burner means.

10 8. A steam generator comprising a setting, a pair of spaced groups of generating tubes in the setting, a furnace chamber arranged between the steam generating tube groups, burner means for firing said furnace chamber, another furnace chamber in the setting disposed adjacent tubes of one of said tube groups and outside said first-mentioned furnace chamber, other burner means adjacent the first-mentioned burner for separately firing said other chamber, a single combustion gas outlet flue at the outer side of the other tube group and arranged to receive all of the gases flowing from both furnace chambers, said flue being so located that the heating gases from the other furnace chamber flow over both of the tube groups and through the first-mentioned furnace chamber before entering the flue, and baffle means positioned in said one of the tube groups, the baffle means being of such depth adjacent the burner means as to prevent gases from the other furnace from flowing over the first-mentioned burner means, the baffle decreasing in depth to such an extent in a direction away from the burners as to enable gases from said other furnace to enter the ignition and combustion zone of said first-mentioned furnace beyond the burner means therefor in the direction of flow of gases in said zone and mix with gases flowing from said burners to thereby become distributed throughout an area of the first-mentioned furnace chamber which gradually increases in a direction away from the burner means.

15 9. A steam generator comprising a setting, a pair of spaced groups of generating tubes in the setting, a furnace chamber arranged between the steam generating tube groups, burner means for firing said furnace chamber, another furnace chamber in the setting disposed adjacent tubes of one of said tube groups and outside said first-mentioned furnace chamber, other burner means adjacent the first-mentioned burner for separately firing said other chamber, a single combustion gas outlet flue at the outer side of the other tube group and arranged to receive all of the gases flowing from both furnace chambers, said flue being so located that the heating gases from the other furnace chamber flow over both of the tube groups and through the first-mentioned furnace chamber before entering the flue, and a refractory baffle plate positioned in said one of the tube groups, the baffle plate being of such depth adjacent the burner means as to prevent gases from the other furnace from flowing over the first-mentioned burner means, the baffle decreasing in depth to such an extent in a direction away from the burners as to enable gases from said other furnace to enter the ignition and combustion zone of said first-mentioned furnace beyond the burner means therefor in the direction of flow of gases in said zone and mix with gases flowing from said burners to thereby be-

come distributed throughout an area of the first-mentioned furnace chamber which gradually increases in a direction away from the burner means.

10. A steam generator comprising a setting, an upper steam and water drum, a pair of spaced lower water drums, a bank of inclined steam generating tubes connecting said upper drum to one of said lower drums, a group of steam generating tubes connecting the upper drum to the other of said lower water drums, a substantially vertically extending baffle plate positioned in said group of steam generating tubes to divide the space between said tube bank and said tube group into a furnace chamber and another furnace chamber laterally adjoining said first-mentioned furnace chamber, burner means for firing the first-mentioned furnace chamber, other burner means adjacent the first-mentioned burner for independently firing the other furnace chamber, said burner means and said other burner means being disposed to direct a stream of gases of combustion in a horizontal direction, a single combustion gas outlet flue at the outer side of the tube bank and arranged to receive all of the gases flowing from both furnace chambers, said flue being so located that the heating gases from the other furnace chamber flow over the tube group, the tube bank and through the first-mentioned furnace chamber before entering the flue, said baffle plate at the end thereof adjacent said burners extending upwardly to a point beyond the burners to prevent gases from the other furnace from flowing over the first-mentioned burner means, the upper edge of the baffle being tapered to such an extent from a point adjacent the burners in a direction away therefrom as to provide a flow area for gases from said other furnace chamber which area gradually increases in a direction away from the burner means and through which gases from the other furnace enter the ignition and combustion zone of said first-mentioned furnace beyond the burner means therefor and mix with gases flowing from said burners to thereby become distributed throughout an area of the first-mentioned furnace chamber which gradually increases in depth in a direction away from the burner means.

11. A steam generator comprising a setting, a pair of laterally spaced groups of generating tubes in the setting, a furnace chamber arranged between the steam generating tube groups, one of said tube groups having at least two adjacent rows of tubes, burner means for firing said furnace chamber, another furnace chamber in the setting disposed adjacent tubes of said one of the tube groups and outside said first-mentioned furnace chamber, other burner means adjacent the first-mentioned burner for separately firing said other chamber, said burner means and said other burner means being disposed to direct a stream of gases of combustion in a horizontal direction, and a single combustion gas outlet flue at the outer side of the other tube group and arranged to receive all of the gases flowing from both furnace chambers, said flue being so located that the heating gases from the other furnace chamber flow over both of the tube groups and through the first-mentioned furnace chamber before entering the flue, and a substantially vertically extending baffle means comprising at least two adjacent rows of tubes of said one of the tube groups in engagement with one another to form a baffle throughout a portion of the length of said tubes, the engaging portion adjacent the

burners being such that the first-mentioned burner means is shielded from the gases from said other furnace chamber, the engaging portion of said tubes becoming less in a direction away from the burners to such an extent as to enable gases from said other furnace to enter the ignition and combustion zone of said first-mentioned furnace beyond the burner means therefor in the direction of flow of gases in said zone and mix with gases flowing from said burners to thereby become distributed throughout an area of the first-mentioned furnace chamber which gradually increases in a direction away from the burner means.

15. A steam generator comprising a setting, an upper steam and water drum, a pair of spaced lower water drums, a bank of inclined steam generating tubes connecting the upper drum to the one of said lower drums, a group of steam generating tubes connecting the upper drum to the other of said lower water drums, said group of tubes having at least two adjacent rows of tubes, said adjacent rows of tubes being in engagement with one another to form a substantially vertically extending baffle which divides the space between said tube bank and said tube group into a furnace chamber and another furnace chamber laterally adjoining said first-mentioned furnace chamber, burner means at one end of said furnace chamber positioned to direct a stream of gases of combustion in a substantially horizontal direction toward the opposite end thereof, other burner means for separately firing said other furnace chamber disposed at the same end of the setting as the first-mentioned burner means to direct a stream of gases of combustion in a substantially horizontal direction toward the opposite end of the setting, a single combustion gas outlet flue at the outer side of said tube bank and arranged to receive all of the gases flowing from both furnace chambers, said flue being so located that the heating gases from the other furnace chamber flow over the tube group, the tube bank and through the first-mentioned furnace chamber before entering the flue, the engaging portion adjacent the burners being such that the first-mentioned burner means is shielded from the gases from said other furnace chamber, the engaging portion of said tubes becoming less in a direction away from the burners to such an extent as to enable gases from said other furnace to enter the ignition and combustion zone of said first-mentioned furnace beyond the burner means therefor in the direction of flow of gases in said zone and mix with gases flowing from said burners to thereby become distributed throughout an area of the first-mentioned furnace chamber which gradually increases in a direction away from the burner means.
